UNITED STATES PATENT OFFICE.

JOHN PEARSON, OF CHICAGO, ILLINOIS.

CAR CONSTRUCTION.

Application filed December 9, 1921. Serial No. 521,118.

To all whom it may concern:

Be it known that I, JOHN PEARSON, a citizen of the United States, residing at Chicago, in the county of Cook and State 5 of Illinois, have invented certain new and useful Improvements in a Car Construction, of which the following is a description.

My invention belongs to that general class of devices known as car constructions, 10 and relates particularly to an improved dump car construction. The invention has among its objects the production of a device of the kind described that is simple, compact, convenient, efficient, durable and satisfactory for use wherever found applicable. The invention has particularly among its 15 objects the production of improved dumping mechanism for controlling the lowering and raising of the dump doors and locking the same in position. Many other objects and advantages of the construction herein shown and described will be obvious to those skilled in the art from the disclosures herein given.

25 To this end my invention consists in the novel construction, arrangement and combination of parts herein shown and described, and more particularly pointed out in the claims.

30 In the drawings, wherein like reference characters indicate like or corresponding parts,

Fig. 1 is a cross sectional view of a car embodying my improved construction, the 35 doors at one side of the car being closed, and those at the other side opened;

Fig. 2 is a side elevation of the same; partly in section;

Fig. 3 is a section taken substantially on 40 line 3-3 of Fig. 2;

Fig. 4 is a view similar to that shown in Fig. 2, with the doors lowered;

Fig. 5 is a section taken substantially on 45 line 5-5 of Fig. 2;

Fig. 6 is a section taken substantially on line 6-6 of Fig. 2;

Fig. 7 is a section taken substantially on 50 line 7-7 of Fig. 3;

Fig. 8 is a section taken substantially on line 8-8 of Fig. 2;

Fig. 9 is a detail in perspective of the locking hook;

Fig. 10 is a detail in perspective of the guide for the slideable bar; and

Fig. 11 is a plan view of the car as seen 55 from above.

In the preferred embodiment of the invention, as illustrated in the drawings, the running gear or trucks, brake mechanism, etc. are not illustrated, inasmuch as the 60 same is not required for the purpose of describing the present invention, and furthermore, the same may be of any preferred or standard construction. The main frame of the car body may also be considerably modified from that shown in the drawings without departing from the invention, although the construction illustrated is preferred and is believed to be in itself new and novel.

65 In the preferred construction, a center beam 1, preferably of I form, is extended lengthwise of the car, the draft rigging being ordinarily secured thereto at each end. A channel bar 1' is shown secured to the top flange of the center beam 1, with 70 the side flanges 2 extending downwardly, so as to overlie the top flange of said center beam. Carried by the center beam 1 are body cross beams 3, the body frame being carried by the body bolsters 4. These 75 several parts are secured to the center beam in any desired manner, and the center beam itself may be constructed in a variety of ways, as for instance, two channels arranged back to back, or the like. The outer ends 80 of the beams 3 are cut away to form shoulders to receive angle beams 5-6 extending lengthwise and preferably from end to end of the car. The beams as shown also carry the side stakes 7. The form of stake 85 shown is constructed at its lower end so as to embrace the beams 3, and is secured in any desirable manner. It will be noted that by securing the stakes in place as shown, the necessity of brackets, gusset plates and 90 the like, is done away with, and a greater clearance obtained. Secured to the stakes 7 95 are the side walls 8 of the car, which are offset at their lower ends, as most clearly shown in Figs. 1, 5 and 6, the offset being 100 indicated at 9, and the side walls secured to the sides or legs 6 of the angle bars.

105 Any number of doors 10 may be arranged at the bottom forming the floor of the car, and in the construction shown, they are arranged from end to end of the car and pivotally supported on axes extending lengthwise of the car, the pivotal support being

substantially at the center of the car. Each door 10, as shown, is formed with hinge parts 11 which are pivotally secured to brackets 12 carried by the channel mounted on the center beam 1, or in an equivalent manner. In the form shown, the doors when closed are below the tops of the beams 3, there being flanged openings 13 in the floor of the car adapted to be covered by said doors, the flange at said opening extending downwardly, as shown. When the doors are raised, they form the floor of the car, and as will be noted, when closed, are slightly below the top of the I beam. This is especially advantageous because when the car is loaded with lumber, structural iron or the like, the articles will bridge over the door openings and transmit the load solely to the bolster and beams. Thus the doors will not be loaded nor as liable to strain, bending or breakage as when the load in the car rests thereon. Each of the doors 10 is constructed in any suitable manner, and each preferably has one or more support or brace bars 14 preferably of angle iron formation and extending transversely of the door at right angles to its hinged edge and projecting beyond the free edge of the door as at 15. The projecting portion 15 of each angle bar 14 is bent slightly downwardly and outwardly of the door, and an eye-bolt 16, or other suitable fastening device, is secured to the projecting portion 15 of the bar to receive one end of a chain or other flexible member 17, as will be hereinafter described.

The raising and lowering of the doors is controlled by the chains 17, or by cables or the equivalent, suitably secured to and extended from the edge of the door, the same supporting the free edge of the door when open, one end of each chain being secured to the eye-bolt 16, as shown. The other ends of the chains are secured by means of an eye-bolt 18, or the like, to a slidable bar 23, which is slidably arranged on the angle 5—6, or its equivalent as shown, there being one or more bars 23 on each side of the car. In the preferred construction I control the operation of a portion of the doors on each side of the car from one end of the car, and the remaining doors from adjacent the other end of the car. This, however, is a matter of preference, as the doors, or the raising and lowering of the same, may be controlled, for example, from one end only, or from a point intermediate the ends if so desired.

As most clearly shown in Figs. 5 and 6, the leg 5 of the angle iron 5—6 is formed with a series of spaced, elongated openings or apertures 18' therethrough, and arranged at each opening is a sheave member 19, which is formed with side flanges 20 having a space 21 therebetween (see Fig. 8). Each of the sheaves 19 is rotatably mounted on a pivot pin 22 secured to the angle member

5—6 in any suitable manner. The sheaves 19 slidably and rotatably support the chains 17 between their ends, that is, between the eye-bolts 16 and 18. The slidable bar 23 is preferably, but not necessarily L-shaped, or in angle-iron form, as shown more clearly in Figs. 5 and 6, the horizontal flange being indicated at 24. A series of elongated openings 28 are formed in the flange 24, the metal at one end of the opening being turned or bent to form abutment ears 28' if desired.

Arranged at suitable points longitudinally of the sides of the car, and as shown, at each of the stakes 7 and secured thereto, are guide members 25, said guide members having a slot or groove 26' therethrough (see Fig. 10), to slidably receive and engage the free edge of the leg 24 of the slid- 85 able bar 23. These guide members 25 may be secured to the stakes 7 by rivets or other suitable or equivalent fastening means.

A pawl or hook having ends 26 and 27 is pivoted intermediate said ends on each of the pivot pins 22, the upper end 27 adapted to project through elongated apertures 28 formed in the flange 24 of the slidable bar 23 so that as the bar is moved, it will strike and rotate the series of locking hooks 26—27, as will be more clearly hereinafter 95 described. Each hook has a cam surface 34 at its lower end 26, and a cut away edge 35 at its upper end 27.

The bar 23 at one end as shown or at any point intermediate the ends is secured to a member 29, which is formed with a threaded portion 30. The threaded portion 30 is in threaded engagement with an internally threaded member or mandrel 31. The mandrel 31 is externally threaded, but in the opposite direction and arranged to threadedly engage a bracket or drum 32 suitably secured to the car, as for instance, by being extended tangentially, and securing this tangential extension to the upper end of the leg 6 of the beam 5—6 (Figs. 5 and 6). The threaded member 31 is formed as at 33, substantially similar to a capstan, so that it may be engaged by an operating bar or the like to shift the same, or rotate it in either direction. The parts may be arranged with either end toward the center of the car.

The operation of the device may be briefly described as follows: Assuming that the doors are in the position shown in Figs. 2, 5, 6 and 7, that is, the doors are closed or raised, then to drop the doors, the capstan (see Fig. 7) is engaged by a rod or the like and rotated. Because of the threaded engagement, the same will move through the bracket, as indicated, to the left (see Fig. 4). The threaded rod 30 in engagement therewith on the interior, being oppositely threaded and prevented from rotating by its rigid connection to the slidable bar 23, will 130

also move lengthwise, to the left, in relation to the member 31, and as shown in Fig. 4, it will be particularly noted that by constructing the rod 30 and the member 31 as shown, the same are double acting, that is, as the member 31 is rotated, it moves lengthwise, and at the same time, owing to its threaded engagement with the rod 30, that is moved lengthwise, not only with movement of the member 31 lengthwise, but owing to the threaded engagement, the rod 30 is also advanced relative to the member 31. As the parts move, the slideable bar 23 is of course moved until the rear wall of the apertures 28, that is, the right hand end of the aperture, positively engages the tiltable hooks 26-27 to tilt them about the pivot pins 22, thus releasing the doors 10 and holding the hooks inoperative.

To raise the doors, the reverse operation takes place, that is, the bar 23 will be moved to the right, lifting the doors by means of the chains 17 until the doors are almost fully or completely closed, at which time the bent ears 28' at the forward end walls of the elongated apertures 28 has positively engaged and tilted the hooks 26-27 about the pivot pins 22, causing the tapered or cam surfaces 34 of the hooks to engage the projections 15 of the brace rod 14 with substantially a camming action to move the door 10 toward the floor so as to clamp it thereagainst.

It will be noted that the rear ends of the upper portion 27 of the hooks have been chamfered or cut away as at 35, so that when the slideable bar 23 is moved to the left, said bar will pivotally move the hooks to tilt them out of the way to disengage from the holding engagement with the doors and hold them inoperative as the slideable bar continues to move past the hooks, as shown in Fig. 4. When the doors are raised, the upper ends of the hooks will reengage in the apertures 28 and be positively actuated when the doors have been substantially completely lifted to cause the camming action or final locking of the hooks as just described.

It will be noted that there is no strain whatever on the chains in so far as supporting the closed doors is concerned. Neither is there any direct transverse strain on the slideable bar 23, as the entire load is supported by the angle beam 5-6. It should be noted that the threaded or screw construction for operating the sliding door, in itself, forms a most simple and efficient locking mechanism, and that by means of it the doors may be supported at any point intermediate their extreme positions of up or down.

Having thus described my invention, it is obvious that various immaterial modifications may be made in the same without de-

parting from the spirit of my invention; hence I do not wish to be understood as limiting myself to the exact form, construction, arrangement and combination of parts herein shown and described, or uses mentioned.

What I claim as new and desire to secure by Letters Patent is:

1. In a dump car, a door, means slidably movable on said car for controlling the movement of said door, and a hook pivotally mounted on said car, engageable with said door to hold it in raised position, said slideably movable means positively actuating said hook to its door-engaging position. 75
2. In a dump car, a door hinged thereto at one edge, means slideable on said car for controlling the movement of said door, and a hook pivotally mounted on said car and engageable with said door at its free edge 80 to hold it in raised position, and positively actuated by said means to control the door-engaging and releasing movement of said hook. 85
3. In a dump car, a door hinged thereto, a bar slideable on said car frame, a flexible member connected at one end directly to said door and at its other end to said slideable bar and controlled thereby, and a hook controlled by said slideable bar to lock said 90 door in its lifted position. 95
4. In a dump car, a door hinged thereto, a bar slideable on said car frame, a flexible member connected at one end directly to said door and at its other end to said slideable bar and controlled thereby, and a hook mounted on the car frame controlled by said slideable bar and operative at substantially 100 the end of the lifting movement of the door to lock said door in its lifted position. 105
5. In a dump car, a door hinged thereto, a bar slideably mounted on said car frame, a flexible member connected at one end directly to said door and at its other end to said slideable bar and controlled thereby, and a hook controlled by said slideable bar and normally inoperative except at substantially 110 the end of the lifting movement of the door to lock said door in its lifted position and to positively release said hook to lower said door. 115
6. In a dump car, a door hinged thereto at one edge, a bar slideable on said car frame, a flexible member connected at one end directly to said door and at its other end to said slideable bar and controlled thereby, and a hook pivoted on said car frame and positively actuated by said slideable bar in one direction of movement at substantially 120 the end of the lifting movement of the door to lock said door in its lifted position and actuated in the other direction of movement to positively release itself from said door. 125
7. In a dump car, a door hinged thereto at one edge, means for lifting said door, and 130

hooks on a stationary part of said car, operable by said lifting means only at substantially the completion of said lifting and having cam surfaces engageable with said door to hold it raised.

8. In a dump car, a door hinged thereto at one edge, a rod slidably mounted on said car, flexible chains connected at one end directly to said door and at the other end to said slidable rod and operated thereby, and hooks on said stationary car frame operable by said slidable rod at substantially the end of the lifting movement of said door to lock said door in position.

15 9. In a dump car, a door hinged thereto at one edge, a slotted rod slidably mounted on said car, flexible chains connected at one end to said door and at the other end to said slidable rod and operated thereby, and hooks on said car projecting through said slot so as to be positively actuated by said slidable member at substantially the end of the lifting movement of said door to lock said door in position.

25 10. In a dump car, a door hinged thereto, a slidable bar on said car, flexible chains operably connecting said door to said bar, hooks fixed on a stationary part of said car

and adapted to be actuated by said bar at substantially the end of lifting of said door to lock it in position, and also adapted to be actuated at substantially the beginning of movement of the bar in the opposite direction to release said hook to permit said doors to drop.

30 11. In a dump car, a door hinged thereto, a slotted slidable bar on said car, flexible chains operably connecting said door to said bar, hooks pivoted on said car and adapted to project through said slot and be actuated by engagement with the end walls thereof in both directions of reciprocation of said bar at substantially the end of lifting of said door to lock it in position, and at substantially the beginning of movement of the 40 bar in the opposite direction to release said hook and hold it inoperative to permit said doors to drop.

35 45 In testimony whereof, I have hereunto signed my name in the presence of two subscribing witnesses.

JOHN PEARSON.
